UNITED STATES PATENT OFFICE.

SARAH E. GRIGGS, OF WOODLAND, CALIFORNIA.

DISPLAY-HOLDER FOR HATS.

SPECIFICATION forming part of Letters Patent No. 643,266, dated February 13, 1900.

Application filed July 14, 1899. Serial No. 723,861. (No model.)

To all whom it may concern:

Be it known that I, SARAH E. GRIGGS, a citizen of the United States, residing at Woodland, county of Yolo, State of California, have 5 invented an Improvement in Display-Holders for Hats; and I hereby declare the following to be a full, clear, and exact description of the same.

My invention relates to a holding and display stand which is especially designed for holding and exhibiting trimmed hats.

It consists of curved elastic arms divergent outwardly and upwardly from a socket-piece and having concavo-convex transversely-disposed spreaders upon the upper ends, said arms being also formed with loops intermediate of their length to form finger-holds by which they may be compressed toward each other to remove or replace the hat upon the 20 spreaders and with elastic coils at the base interposed between the socket and the lower ends of the arms.

The invention also comprises details of construction, which will be more fully explained 25 by reference to the accompanying drawings, in which—

Figure 1 is a view showing the arms with the spreaders, socket-piece, and the intermediate finger-loops. Fig. 2 shows the device 30 with the addition of the coiled springs at the base of the arms. Fig. 3 is a top view of Fig. 2.

Various display-stands have been employed for the purpose of exhibiting articles thereon having fixed bases and depending upon the 35 elasticity of the comparatively straight wires of which they are formed.

The object of my invention is to provide a convenient removable attachment for any sort of base-bracket or other holder made of sufficiently stout wires and providing for the requisite elasticity by forming within the length 40 of the wires and at their base a sufficient number of coils for the purpose and, in addition, to provide finger holds or loops by which the 45 arms can be compressed toward each other for the purpose of easily removing or replacing the hat without damage to the fragile structure.

A is a socket-piece which may be formed of 50 a tube of metal, or it may be formed by coiling the wires B, which form the diverging upturned arms, and afterward soldering or

otherwise uniting the coils together. This socket is adapted to fit upon any straight or other supporting standard or the upturned 55 arm of a wall-bracket or other like holding device. The wires B are bent at the upper ends, so as to form the transverse curved spreaders C. These spreaders are convex upon the outside and correspondingly concaved upon their 60 inner sides and are of sufficient length, so that when the arms expand them within the band or interior of the hat they will have sufficient contact-surface and holding force to hold the hat firmly in place. These arms B 65 are preferably curved outwardly from the socket A, to which they are attached, and at points intermediate between the upper and lower ends are formed the loops or finger-holds D, preferably by giving the arms B a 70 single turn at the point where the loops are to be formed, making the loops of sufficient size to receive the thumb and finger of the hand, so that by pressing upon the loops the arms can be forced inwardly to release the 75 hat, or in replacing it after the hat is in the proper position by releasing the finger-holds the arms will spread out and the parts C will grasp and hold the interior of the hat.

To avoid the inconvenience and expense of 80 making the arms B sufficiently long to provide the necessary elasticity, I have shown these arms as bent to form one or more coils E at the point where they join the base, and by means of these coils the arms, which must 85 be made of sufficiently stout wire to have the required stiffness to support the articles, will be rendered much more elastic and easy to manipulate and are not liable to become set 90 when pressed together for the purpose of removing or replacing the articles supported thereon.

Having thus described my invention, what I claim as new, and desire to secure by Letters Patent, is—

1. A hat holding and display device consisting of arms having their lower ends provided with a vertical socket, and curving outwardly and upwardly therefrom, with transverse concavo-convex spreaders formed upon 100 the upper ends, said arms having the open finger-loops intermediate between the top and bottom.

2. A hat holding and display device con-

sisting of segmentally-curved arms united at the base and provided with a vertical socket-piece said arms having transversely-curved concavo-convex spreaders upon the upper ends, and elastic coils and finger-loops formed in the arms intermediate between the upper and lower ends thereof.

3. A hat holding and display device consisting of segmentally-curved arms uniting and forming a vertical socket-piece at their junction, transverse spreaders and supports formed at the upper end, and elastic coils formed by turns of the wire at their meeting-points and above their junction with the socket-piece.
- 15 4. A hat holding and display device con-

sisting of segmentally-curved wires having transversely-curved concavo-convex spreaders and holders at the upper end, finger-loops formed by giving the wires a single turn intermediate between the upper and lower ends, one or more coils formed at the lower ends of the wires and axially in line with each other, said wires being continued downwardly from the coils and provided with a vertical socket-piece.

In witness whereof I have hereunto set my hand.

SARAH E. GRIGGS.
